UNITED STATES PATENT OFFICE.

FEED W. STORK, OF SAGINAW, MICHIGAN, ASSIGNOR TO STORK ENGINEERING AND MANUFACTURING COMPANY, OF SAGINAW, MICHIGAN, A CORPORATION OF MICHIGAN.

SCREW JACK.

Application filed August 3, 1925. Serial No. 47,849.

This invention relates to screw jacks for automobiles and the like and the improvement pertains more particularly to the arrangement of the base of the jack and its 5 associated parts.

The objects are to provide, in conjunction with a compact gear case, a pair of oppositely disposed removable covers that are secured to the sides of the base by a through bolt, which is arranged so as to permit easy 10 removal and replacement of the covers for access to the gears, and also acts as a gear-retaining device, keeping the gear from tilting upward or tending to climb the rectangular screw-operating shaft when the 15 jack is in operation.

By means of the through bolt the actuating gear is always kept in proper meshing relation to the pinion by which the gear is 20 rotated.

With the foregoing and certain other objects in view, which will appear later in the specifications, my invention comprises the devices described and claimed and the equivalents thereof.

Fig. 1 is a side view of a screw jack embodying my improvement.

Fig. 2 is a part sectional side view of the base, showing the screw actuating gear and pinion, the jack screw being in its lowered position.

Fig. 3 is a perspective view of a pair of oppositely disposed removable cover plates for the sides of the base, the plates connected by a bolt arranged and operating in accordance with my invention.

Fig. 4 is a part sectional detail of the gear and the square shaft upon which the jack screw travels up and down, the screw 40 shown in its extended position.

As is clearly shown in the drawings, the device is applied to the body 1 of a screw jack, the base of which is made in the form of a gear case open at the sides.

Numeral 2 indicates the usual crank-receiving socket in the hub of the operating pinion. The jack screw 3, as is customary in this class of implements, is slidable up and down on a square central shaft, the shaft being rotated by the gear. When the screw 50 is retracted its lower end 3a rests upon the gear and when it is raised, as shown in Fig. 4, its lower end is clear of the gear.

My present improvement relates particularly to a simple and novel means, namely,

the gear case cover 4, 4 and the through bolt 5, by which the gear 6 is kept from tilting when the screw 3 is not in contact with the gear, as shown in Fig. 4. The gear is turned by the usual pinion 7, preferably by a suitable handle engaging the socket 2. The upright central shaft 8 is preferably secured to and is driven by gear 6. It turns the screw 3 when the jack is in operation, the function and mode of operation of the screw being that of the ordinary screw jack.

When the covers 4, 4 are removed the entire interior of the base, including the gears and the end of the screw, are opened for inspection. When the covers 4, 4 are in 70 place and held by bolt 5, shown in Fig. 1, and the screw 3 is raised clear of the gear 6, as shown in Fig. 4, the bolt 5 effectually prevents any tendency for the gear 6 to tilt and thus disturb the proper running alignment of the gear and pinion 7.

The bolt 5 is, as shown, located above and in proximity to the upper face of the gear and opposite the pinion 7. By this means there is no tendency for the jack when under load to bind and operate with difficulty, as would be the case when gear 6 is not provided with means for preventing tilting, and the means herein shown, namely, the bolt 5 mounted in the covers 4, 4 is a simple, yet effective device for accomplishing this result, and one that does not interfere with the removal or replacement of the working parts of the jack. The working parts of this jack can be assembled rapidly and cheaply when produced in large quantities, because the gear 6 and pinion 7 can be inserted in the base by merely dropping them into place from either side, then when the covers 4, 4 are placed the bolt 5 becomes 90 also a gear-retaining element.

In the foregoing description and in the drawings I have set forth and illustrated my invention as constructed with two removable covers, this being the preferred construction. It would be possible, however, and in some cases possibly advisable, to make the jack with one of the covers not removable, that is to say, either permanently fixed or cast integral with the side of the gear case. The construction and mode of operation of the other cover and the through bolt would, however, be the same in both arrangements. Therefore, I desire it to be understood that a single removable cover 105 110

and the through bolt 5 may be employed if desired, without departing from the spirit of my invention as herein set forth and claimed.

5 Having thus described my invention, what I claim and desire to secure by Letters Patent is:

1. In a screw jack, a body, the base of which comprises a gear case, a screw arranged to operate in said body, a gear and a co-acting pinion in said case, a pair of oppositely disposed removable gear case covers, a bolt extending through the base and connecting said covers, that part of said bolt
- 10 within the base being located in proximity to the upper face of the gear and opposite the pinion, whereby said bolt serves to re-

tain said gear in operating relation to said pinion.

2. In a screw jack, a body, the base of which comprises a gear case, a screw arranged to operate in said body, a gear and a co-acting pinion in said case, a removable gear case cover, a bolt extending through the base and connecting said cover with the opposite wall of said case, that part of said bolt within the base being located in proximity to the upper face of the gear and opposite the pinion, whereby said bolt serves to retain said gear in operating relation to said pinion.

In testimony whereof, I affix my signature.

FRED W. STORK.
